HYDRAULIC COPYING DEVICE FOR LATHES

Ottomar von Zelewsky, Neuhausen am Rheinfall, Switzerland, assignor to Georg Fisher Aktiengesellschaft, Schaffhausen, Switzerland, a company of Switzerland

Application April 18, 1950, Serial No. 156,537
In Switzerland November 30, 1949

6 Claims. (Cl. 60—52)

1

This invention relates to a copying lathe and relates more particularly to a lathe comprising an hydraulic system for the operation of the tool. Lathes of this type are provided with a follower which cooperates with a steering pin and which regulates the pressure of a fluid flowing continuously on both sides of a differential piston located in a slide. The follower moves in engagement with a template or prototype held upon suitable supports and causes corresponding movements of a tool-carrying casing slidable upon the aforesaid slide.

An object of the present invention is the provision of an hydraulic system operatively connecting the follower with the tool holder which is efficient and durable in operation.

Other objects of the present invention will appear more clearly from the following specification.

The objects of the present invention may be carried out through the provision of an hydraulic system wherein inflow and outflow of the pressure medium in a chamber located above the operating pin which is engaged by the follower is regulated through the movements of said regulating pin.

The invention will appear more clearly from the following detailed description, when taken in connection with the accompanying drawing showing, by way of example, a preferred embodiment of the inventive idea.

The drawing is a diagram illustrating the hydraulic system of the lathe in section, and other parts in side elevation.

The copying lathe illustrated diagrammatically in the drawing includes a frame 1 carrying a longitudinal track 2 and a carriage 3 which is moved upon the track 2 by any suitable means not shown in the drawing. A work piece 7 is supported along its axis 4 between a headstock 5 and a tailstock 6. The carriage 3 is slideable in directions parallel to the axis 4. The carriage 3 carries guides 8 and 9 which are firmly mounted thereon, and upon which slides a carriage or slide 10. The slide is integral with a tool holder 15 which carries a tool 16 used to shape the work piece 4 in conformity with the outlines of a template 23.

The template 23 is carried by a template holder 22 which is held firmly by supports 20 and 21, indicated diagrammatically in the drawing, and carried upon the machine frame 1.

The hydraulic device used to transmit the movements of the follower 27 to the tool 16 includes a differential piston 12 which is attached by flanges 11 and bolts 11a to the carriage 3. The differential piston 12 slides in bores 13 and 14 of the casing 16.

2

A container 17 for the pressure fluid is carried by the casing 3 which supports a pump 18 communicating with the interior of the container 17 and adapted to transmit fluid through a pipe 19 into the annular space 35.

A steering casing 26, which is partly constructed as a differential piston, is located within the casing 10 and is adjustably connected therewith by a threaded spindle 25, one end of which 10 is screwed into a corresponding threaded opening of the casing 26 while the other end extends through the top of the casing 10 and is firmly connected with a hand wheel 24 located outside of the casing 10.

15 The follower 27 is swingably mounted upon a pivot 28 carried by the casing 26. The inner end of the follower 27 is in engagement with a steering piston or valve pin 29 which is reciprocably mounted in a bore or space 45 provided in the casing 26. In the example illustrated the valve pin 29 consists of two parts which are slideable in the space 45 and which are joined by a thinner rod 29a. Due to this arrangement a chamber 32 is formed within the casing 26 which may be in communication with a passage 41 or a passage 31, depending upon the position of the valve pin 29. The passages 31 and 41 are formed in the casing 26. The passage 31 leads from the chamber 32 to a space 33 located between the casing 26 and an inner wall of the casing 10.

20 A threaded needle valve 34 is carried by the casing 26 and extends between the space 33 and the space 45 behind the valve pin 29. A passage 45a extends between the needle valve and the passage 31.

25 A spring 30 is located within the space 45 and engages the bottom of the space 45 and the bottom of the pin 29, pressing the pin against the follower 27.

30 The needle valve 34 is used to regulate the flow of the pressure fluid between passages 31 and 45.

The conduit 19 leads to an annular space 35 provided within the casing 10 around the piston 12. Furthermore, the conduit 19 is in communication with a pressure-regulating valve 36 which 45 also operates as a relief valve, and which is pressed upwardly by a spring 37.

35 A chamber 38a located directly above the valve 36 may communicate with a passage 38 formed in the piston 12, and communicating with a space 44 extending between the piston 12 and the casing 10.

40 Another passage 39 connects the space 44 with an annular space 40 extending around the casing 26.

45 The passage 41, which is in communication

with the space 48, leads to an edge 43 provided in the valve pin 29.

A conduit 42a is formed in the casing 10 and connects the space 33 with a conduit 42 by means of which fluid is returned to the container 17.

This hydraulic copying device is operated according to the following principles:

The pump 18 operates continuously so that there is a constant flow of the hydraulic medium. In the course of the movement of the slide or casing 3 the follower 27 slides upon the surfaces of the template 23. Since the follower 27 is in contact with the valve pin 29, a swinging movement of the follower 27 will be transmitted to the valve pin 29, the position of which will regulate the division of pressure in the space 44 above the piston 12 and the space 35 below the piston 12. It should be noted that the movements of the pin 12 are in the order of a few hundredths of one millimeter in any one direction and yet they suffice to provide a proper division of the pressure of the hydraulic fluid, whereupon the pin moves into its middle position.

The pump 18 pumps the pressure medium out of the container 17 through the conduit 19 into the annular space 35 extending around the piston 12. At the same time fluid will flow to the chamber 38a and will be accumulated there until its pressure becomes greater than the pressure of the spring 37. Then the valve 37 is opened so that the pressure medium can flow into the channel 38 and thence into the space 44, the passage 39, the space 40 and the passage 41.

Should further movement be blocked by the valve pin 29 the pressure in the space 38a will continue to grow until the spring 37 is compressed still further. Then the valve 36 will operate as a relief or overflow valve and will allow the return flow of the pressure fluid through the conduit 37a into the container 17. Thus, the valve 36 maintains an adjustable, constant pressure in the annular chamber 35 during the copying operation. It should be noted that the fluid pressure prevailing in the annular chamber 40 presses downwardly the casing 26 which is connected with the casing 10 by means of the threaded spindle 25. This downwardly asserted pressure prevents any possibility of play between the casing 26 and the threaded spindle 25.

Fluid pressure provided in the chamber 44 by the pump 18 will move upwardly the casing 10 in relation to the immovable piston 12 until this pressure is balanced.

It is apparent that the casing 26 will move upwardly along with the casing 10. Fluid pressure will be balanced and the upward movement will cease when the follower 27 is moved into engagement with the template 23. As the result of this engagement with the template the follower 27 will swing about its pivot 28 so that the valve pin 29 will move upwardly, thereby compressing the spring 30. The edge 43 of the valve pin 29 will move upwardly so that connection will be provided between the channel 41 and the channel 31. Fluid will then flow through the channel 31, the space 33 and the conduits 42a and 42 into the container 17. This will produce a drop in pressure in the space 44 located above the piston 12 and since pressure in the chamber 35 is maintained, the casing 10 will move downwardly.

As already stated, the extent of the movements of the valve pin 29 is very small so that the edge 43 moves back into the position shown in the

drawing and the balance of the system is quickly restored.

The needle valve 34 is utilized to dampen possible oscillations of the casing 10 and to make these oscillations aperiodic. Such oscillations may be caused by friction among the various parts, effects of the forces asserted by the tool 16 and changeable flow properties of the pressure fluid utilized in the system. The needle valve 34 will operate to choke the inflow and the outflow of the pressure medium situated above the valve pin 29 in the space 45, thereby preventing conditions at the edge 43 which would disturb the equilibrium and result in the aforesaid oscillations.

It is apparent that the example shown above has been described solely by way of illustration and not by way of limitation, and that it is subject to many variations and modifications without departing from the scope or intent of the present invention. All such variations and modifications are to be included within the scope of the present invention.

What is claimed is:

1. A hydraulic copying device, comprising, a body; a piston connected with said body, an actuator pivotally mounted in said piston, a steering pin movably mounted in said piston and pressing against said actuator, a regulating valve operatively connected with said steering pin, said piston having a chamber formed therein which is located above said actuator and is in communication with said valve, means pumping fluid to said chamber, and means connected with said valve for removing the pumped fluid when the valve is opened by said actuator.

2. A hydraulic copying device, comprising, a body; a piston connected with said body, an actuator pivotally mounted in said piston, a steering pin movably mounted in said piston and pressing against said actuator, a regulating valve operatively connected with said steering pin, said piston having a chamber formed therein which is located above said actuator and is in communication with said valve, means pumping fluid to said chamber, means connected with said valve for removing the pumped fluid when the valve is opened by said actuator, and a common fluid container for the first-mentioned and second-mentioned means.

3. A hydraulic copying device, comprising, a body; a piston connected with said body, an actuator pivotally mounted in said piston, a steering pin movably mounted in said piston and pressing against said actuator, a regulating valve operatively connected with said steering pin, said piston having a chamber formed therein which is located above said actuator and is in communication with said valve, means pumping fluid to said chamber, means connected with said valve and constituting a passage for removing the pumped fluid when the valve is opened by said actuator and an adjustable needle valve threaded into said piston and extending into said passage.

4. A hydraulic copying device, comprising, a body; a piston connected with said body, an actuator pivotally mounted in said piston, a steering pin movably mounted in said piston and pressing against said actuator, a regulating valve operatively connected with said steering pin, a fixed differential piston located adjacent the first-mentioned piston within said body, a pump communicating with the second-mentioned piston, and means within the second-mentioned piston for transmitting fluid pumped by said

pump to a space between said body and the second-mentioned piston, the first-mentioned piston having formed therein a passage connecting said space with said valve, and another passage connecting said valve with a space between said body and the first-mentioned piston, said body having an exhaust passage formed therein and connected with the second-mentioned space.

5. A hydraulic copying device, comprising, a body; a piston connected with said body, an actuator being pivotally mounted in said piston, a steering pin movably mounted in said piston and pressing against said actuator, a regulating valve operatively connected with said steering pin, a fixed differential piston located adjacent the first-mentioned piston within said body, a pump communicating with the second-mentioned piston, a relief valve within the second-mentioned piston and connected with said pump for transmitting fluid pumped by said pump to a space between said body and the second-mentioned piston, the first-mentioned piston having formed therein a passage connecting said space with said valve, and another passage connecting said valve with a space between said body and the first-mentioned piston, said body having an exhaust-passage formed therein and connected with the second-mentioned space, an exhaust

pipe connected with said exhaust passage, and a fluid container communicating with said pump and said exhaust pipe.

6. A hydraulic copying device, comprising, a body; a piston connected with said body, an actuator pivotally mounted in said piston, a steering pin movably mounted in said piston, said piston having a valve chamber formed therein, a valve body movably mounted in said valve chamber, a spring within said valve chamber pressing said steering pin against said actuator, said piston having another chamber communicating with the first-mentioned chamber, means pumping fluid to the second-mentioned chamber, said piston having a passage formed therein and extending from the first-mentioned chamber to a space between said body and said piston, means connected with said space for removing the fluid and an adjustable needle valve threaded into said piston and extending between said space and the first-mentioned chamber.
